UNITED STATES PATENT OFFICE.

ROBERT ADONIS MAHAN, OF JONESBORO, ARKANSAS.

ELECTRIC INCANDESCENT LAMP.

1,112,306.

Specification of Letters Patent. Patented Sept. 29, 1914.

Application filed March 19, 1914. Serial No. 825,848.

To all whom it may concern:

Be it known that I, ROBERT ADONIS MAHAN, a citizen of the United States, residing at Jonesboro, in the county of Craighead and State of Arkansas, have invented certain new and useful Improvements in Electric Incandescent Lamps; and I do declare the following to be a full, clear, and exact description of the invention, such as 10 will enable others skilled in the art to which it appertains to make and use the same.

This invention relates to improvements in electric lamp holders of that class designed for portable attachments of incandescent 15 lamps for furniture and the like.

The object of the invention is to provide simple, effective, and quickly operated means for varying, regulating, or shutting off entirely the light of incandescent lamps and 20 more especially to those which are arranged in horizontal position.

Another object is to provide a device of this character composed of telescoping shade sections constructed to provide for the rotation of one section about the lamp relatively to the other to permit the passage of more or less light and to direct the rays thereof in any desired direction.

Another object is to provide a simply constructed and efficient universal joint for electric lamps constructed to revolve and the socket to be adjusted and held at any desired angle.

With these and other objects in view, the 35 invention consists of certain novel features of construction, and the combination and arrangement of parts, as will be more fully described and claimed.

In the accompanying drawings:—Figure 40 1 represents a perspective view of what is known to the trade as a "Handy Light" equipped with these improvements. Fig. 2 is a side elevation partly in section showing the lamp mounted on a shelf or similar support. Fig. 3 is a longitudinal section of the universal joint connection. Fig. 4 is an enlarged sectional view of an incandescent lamp equipped with my improved shade. Fig. 5 is a transverse section thereof taken 45 on the line 5—5 of Fig. 4, looking in the direction of the arrow. Fig. 6 is an enlarged sectional view showing the mounting of the lamp shade on the socket thereof. Fig. 7 is a transverse section taken on the line 50 7—7, of Fig. 4 looking in the direction of

the arrow. Fig. 8 is a detail sectional view of the supporting bracket.

In the embodiment illustrated, a lamp socket S of ordinary construction is shown having an incandescent bulb B' mounted 60 therein in the usual manner and on said socket is mounted my improved adjustable shield or lamp shade which comprises a fixed section 1 secured in any suitable manner preferably to the inner face of an annular 65 flange or supporting bracket B carried by the socket S, such as is usually employed for supporting shades for incandescent lamps. This section 1 may be composed of any suitable material and corresponds in shape with 70

the outline of the lamp globe being substantially semi-pear-shaped and preferably having its edges curled or flared outwardly, as shown clearly in Figs. 4 and 5. On the outer face of this bracket B is formed an 75

annular groove or seat 2 in which is revolubly mounted a metal band 3 to which is secured a movable shade section 4, similar in shape to the section 1, the side edges of 80 which are also flared in the manner similar to those in the section and which is slightly larger than said section 1 and is adapted to be telescopically engaged therewith as

shown clearly in Figs. 4 and 7. From the above description, it will be obvious that the 85 outer section 4 may be moved around the lamp relative to the section 1 and may overlap it a greater or less extent to vary the

quantity of light permitted to be radiated from the lamp, or if desired, it may be entirely closed as shown in Fig. 5 for completely shutting off the light. The socket 90

S is also revolubly mounted, as is usual in lamps of this character to permit the turning of the fixed section to vary its angles for 95 changing the direction of the light rays from the lamp. This socket S is adapted to be connected with a supporting bracket b by a universal joint shown clearly in Figs. 2, 3 and 7, and by means of which said lamp 100 may be disposed in planes at right angles to each other, if so desired.

The bracket b, which is the bracket now on the market in connection with lamps of this character, is here shown equipped with 105 an auxiliary clamping spring 5 to adapt the bracket for use in connection with thinner shelves than those which could be engaged by the bracket b. This clamping member 5, here shown in the form of a stiff wire 110

spring mounted within the bracket *b*, is shown clearly in Figs. 1 and 2, said spring being shown in detail in Fig. 8 in the form of a U-shaped member having coils 6 and 7 at the free ends of its legs which are provided with laterally extending arms 8 for engagement with suitable sockets in the bracket *b*, the U-shaped portion of said spring being adapted to cooperate with the lower jaw of the bracket *b* for clamping between them any article to which they may be adapted.

In Fig. 3, the improved universal joint used in connection with a lamp of this character is shown in detail in which 10 represents an outer thimble or casing having a bore 11 extending longitudinally therethrough and enlarged at its opposite ends as shown at 12 and 13 forming shoulders 14 and 15 for a purpose to be described. This casing 10 is designed to be connected to the bracket *b* or other suitable bracket by means of a clamping member 16 which is adapted to be threaded into the chamber 12, an annular head 17 extending laterally from its outer end between which and the outer end of the casing 10, the bracket is designed to be clamped, the clamping member 16 having first been passed through an aperture formed in said bracket for the attachment of the lamp. A lamp engaging member 18 is connected with the casing 10 and is constructed in the form of a tubular thimble 19 adapted to be extended through the bore 11 of the casing 10 and held in operative engagement therewith by means of a headed bolt 20, the head of which is disposed in the chamber 12 and abuts against the shoulder 14, the shank passing through the thimble 19 beyond its outer end and there provided with a securing nut 21, which is arranged between two longitudinally extending lateral ears 22 and 23 between which a shank 24 connected with the socket *S* is designed to extend and to be pivotally connected by means of a bolt or other suitable member 25.

The member 18 has a head 26 formed at the upper end of the thimble 19 and which is designed to fit in the chamber 13 of the casing 10, and is adapted to be revolved in said casing on the bolt 20. This head 26 has an annular flange 27 which is designed to overlap and rest on the outer end of the chamber 13, the inner face of said head 26 forming a shoulder or abutment against which one end of a coil spring 28 is designed to bear, said spring 28 being arranged around the thimble 19 within the chamber 13 and bearing at its other end against the shoulder formed by the inner end wall of said chamber 13. This spring 28 exerts its tension to force the member 18 outward, thereby causing the head 20' of the bolt to frictionally engage the shoulder 65 in the chamber 12 formed by the inner wall

of said chamber, and thereby yieldably hold the lamp connecting member 18 in adjusted position, permitting it to be turned in any desired direction.

The ears 22 and 23 are preferably slightly resilient and are adapted to bindingly engage the shank 24 to hold the lamp socket at any desired angle between them.

From the above description, it will be obvious that by the use of this improved universal joint, the lamp mounted in the socket *S* may be adjusted in planes at right angles to each other to position it so that it will throw its light rays in the desired direction.

In the use of this improved holder, the bracket *b* to which it is attached may be engaged with a shelf *s* or any other suitable support as shown in Fig. 2 and the lamp mounted on said bracket may be adjusted at any desired angle. When it has been adjusted to the desired position, the bracket *B* may be turned to position the fixed shield or shade 1 at the point desired and the telescoping or movable shade section 4 may be turned to admit more or less light from the bulb *B'* as may be desired.

The cord carrying the conducting wires preferably enters the socket *D* through one side thereof, as is shown clearly in Figs. 2 and 7, a small insulating socket *S'* being arranged in the opening in the socket *D* through which said cord enters. By so arranging the cord, the necessity of its being connected with the universal joint or lamp connecting element is avoided.

From the above, it will be obvious that this improved shield or shade may be very quickly adjusted, a simple twist of the bracket *B* in one direction carrying both shields and then a backward twist of the band 3 carrying the shield section 4 being all that is required to adjust these shields. The object of this improved shield or shade is to concentrate the light, and the sections thereof may be constructed of brass, steel, aluminum, or any other desired material, and may be secured in any desired manner to the band 3 and bracket *B*.

Having thus described my invention, what I claim is:—

1. An incandescent lamp having a shade bracket mounted thereon, a hollow semi-pear-shaped shield section fixed to said bracket, a band revolvably mounted on said bracket, and a similarly shaped shield section secured to said band, revoluble therewith and adapted to telescopically and laterally engage the other section.

2. An incandescent lamp socket having an annular shade bracket mounted to revolve on said socket, a shade section fixed to the inner face of said bracket, said bracket having an annular seat in its outer face, a band revolvably mounted in said seat, and a shade

section fixed to said band said sections conforming to the shape of an electric light bulb and adapted to telescope laterally.

3. The combination with a supporting member, and an incandescent electric lamp socket having a shank, of a universal joint connection between said socket and support comprising a tubular casing having a reduced central portion with enlarged chambers at its opposite ends, means for securing one end of said casing to said support, a lamp connecting element having a thimble at one end fitting in the reduced portion of said casing with a head revolvably mounted in the outer end of said casing, a coil spring arranged around said thimble in said chamber at the outer end of said casing, a binding element mounted in said casing and engaging said thimble, and means at the outer end of said connecting element for frictionally engaging the shank of said socket.

4. The combination with a supporting member and an incandescent lamp socket having a shank, of a universal joint connection between said socket and support com-

prising a tubular casing having a reduced central portion with enlarged chambers at its opposite ends, means for securing said casing to said supporting member, a lamp connecting member having a thimble extending into the reduced portion of said casing, and a head fitting in the outer chamber thereof, a coil spring arranged in said chamber between said head and the inner end wall of said chamber, a headed bolt extending through said thimble with the head thereof engaging the inner end wall of the chamber at the inner end of said casing, and laterally spaced longitudinally extending apertured clamping ears at the outer end of said lamp connecting element, and means for connecting said ears to the shank of said socket.

In testimony whereof I have hereunto set my hand in presence of two subscribing witnesses.

ROBERT ADONIS MAHAN.
